HIPPOLYT SAURER, OF ARBON, SWITZERLAND.

SHUTTLE-OPERATING MECHANISM FOR EMBROIDERING-MACHINES.

1,347,232.

Specification of Letters Patent.

Patented July 20, 1920.

Application filed November 7, 1919. Serial No. 336,433.

To all whom it may concern:

Be it known that I, HIPPOLYT SAURER, a citizen of the Republic of Switzerland, residing in Arbon, Switzerland, have invented 5 certain new and useful Improvements in Shuttle-Operating Mechanism for Embroidering - Machines, of which the following is a specification, reference being had to the accompanying drawings, forming a part 10 hereof.

In shuttle embroidering machines the shuttles are usually mounted in raceways which are inclined somewhat with respect to the vertical and are reciprocated therein, 15 for the purpose of causing the shuttles and the shuttle threads to pass through the loops of the needle threads, by pins which are carried by a horizontal bar to which the necessary reciprocations in a substantially vertical 20 direction are imparted by suitable mechanism. Each shuttle is actuated by two pins, one of which is below the shuttle and the other above it. When the shuttle thread gives out the shuttle must be removed from 25 the raceway in order to permit a new bobbin to be inserted, and for this purpose the upper pin is movable longitudinally with respect to the shuttle operating bar so that the shuttle can be removed through the upper end 30 of the raceway. Such removals must be effected frequently with the result that there is more or less wear between the shuttle actuating pin and the shuttle operating bar and that, when the pin is mounted, as usual, in a 35 rectangular groove in the upper side of the shuttle operating bar, in which it is held by the pressure of a spring clip, there is eventually developed a looseness or freedom for lateral motion of the pin in its groove. 40 Such looseness or lateral motion may be comparatively slight at the bar, but at the end of the pin, where it co-acts with the shuttle, such looseness becomes relatively considerable, so that the pins do not coöperate prop- 45 erly with the shuttles and the latter are impeded in their free movement in the raceways. Furthermore, the pins, by reason of such looseness, sometimes bear against the shuttles in the upward movement of the 50 shuttles, so that there is not always provided between the upper pin and the shuttle the clearance which is necessary to permit the shuttle to pass through the loop of the needle thread without jamming, which results in 55 the breaking of the needle thread. It is the object of this invention to overcome the diffi-

culties mentioned and to provide for such a bearing of each upper pin on the shuttle operating bar that the wear between the pin and the bar shall be taken up automatically and the development of such looseness of the pin in its bearing as to permit lateral movement of the pin at its shuttle actuating end be prevented. In accordance with the invention there is provided between each pin 60 and the bar a bearing surface which is relatively oblique with respect to the vertical so that, as wear takes place, the pin is nevertheless pressed at all times tightly against the operating bar by its coöperating spring 65 clip and is thereby held from lateral movement, whereas, if the pin is mounted in a rectangular groove, with its side walls vertical, as heretofore, the wear between the pin and such vertical walls is not compensated 70 for and looseness of the pin results therefrom. It will be seen, as this description proceeds, that the oblique surface between the pin and the bar can be provided in various ways and can be either plane or curved and 75 that the pin, variously formed, can be made to lie in a groove of the bar, also variously formed, or that the pin might be formed with a longitudinal groove to coöperate with a suitably formed rib on the bar. The invention 80 will be more fully explained hereinafter with reference to the accompanying drawing in which it is illustrated and in which—

Figure 1 is a detail view in cross-section showing the old method of mounting the 85 shuttle actuating pin in a rectangular groove in the shuttle operating bar.

Fig. 2 is a view mainly in elevation but partly in section showing so much of the shuttle operating mechanism of an embroidery machine as is necessary to enable the application of the invention thereto to be understood, one embodiment of the invention being illustrated in this figure.

Fig. 3 is a view in section on the plane 90 indicated by the broken line III—III of Fig. 2, but on a larger scale.

Fig. 4 is a detail view in section on the plane indicated by the broken line IV—IV of Fig. 3, but on a still larger scale, illustrating the particular embodiment of the invention indicated in Fig. 2.

Figs. 5, 6, 7, 8 and 9 are views similar to Fig. 4, but showing other embodiments of the invention.

The upper and lower shuttle pins 1 and 17 are secured, in the improved construction as

well as in the old construction, to a shuttle operating bar 3, which is mounted, by means of swiveled clips 11, upon reciprocating rods, one of which is shown at 12, guided in suitably inclined guides 13. The lower bar 3 is connected by a link 14 with one arm of a bell crank lever 15 to which an oscillating movement is imparted from suitable mechanism through a rod 16 to effect the substantially vertical reciprocations of the shuttle operating bars. Each shuttle 9 is mounted in the corresponding raceway 10 and is reciprocated therein by the pins 1 and 17, one above the shuttle and the other below it. The lower pin 17 is secured fixedly to the bar 3, but each upper pin 1 is made longitudinally movable so as to permit it to be withdrawn whenever it is necessary to remove the corresponding shuttle from the raceway, as for the purpose of inserting a filled bobbin. For this purpose each upper pin is held to its seat on the operating bar 3 by a screw 17' and a spring clip 18. Heretofore each upper pin 1 has been made rectangular in cross-section and seated in the rectangular groove 2 of the upper end of the bar 3, as indicated in Fig. 1. In this construction whatever looseness is developed between the pin and the bar, due to wear occasioned by frequent moving of the pin in its groove, is not in any way compensated for by the pressure of the spring clip 18 and eventually considerable looseness or lateral play of the pin with respect to the bar is developed and undesirable results follow as hereinbefore explained.

By the present invention each upper shuttle actuating pin is so mounted on the shuttle operating bar that wear between the pin and the bar is constantly and automatically compensated for and no looseness or lateral play of the pin can be developed. This result is accomplished by providing between the pin and the bar a bearing surface which is oblique with respect to the vertical, so that, as wear takes place, the pin and bar are always pressed together at such oblique bearing surface by the spring clip or holding means and no looseness can develop. Such oblique bearing surface can be provided in various ways. As shown in Fig. 4, the pin 1 is slightly flattened, as at 7, and the groove 2, having one vertical side wall 4 and a horizontal bottom surface 5, is formed with an oblique bearing surface 6 with which the flattened surface 7 of the pin co-operates, the pin also bearing, as at 8, against the vertical face 4. It will be seen that the downward pressure of the holding means, such as the spring clip 18, presses the pin always closely against the oblique bearing surface at 6, so that wear between the pin and the bar, whether it be wear of the pin or wear of the bar, is always compensated for and the development of loose-

ness between the pin and the bar is prevented.

The pin 1^a might remain circular in cross-section and rest in a groove 2^a which is V-shaped in section, as shown in Fig. 5, or, as shown in Fig. 6, the round pin 1^b might have two faces flattened, as at 19 and 20 and rest in the groove 2^b which is V-shaped in cross-section. Again, as shown in Fig. 7, the pin 1^c which is rectangular in cross-section, might have its lower edges beveled off and rest in the groove 2^c with correspondingly inclined sides, as at 21, 22. The same result might be accomplished by permitting the pin 1^d, circular in cross-section, to rest in a rectangular groove 2^d, the width of which is less than the diameter of the pin, so that the relatively oblique surfaces of the pin rest against the edges of the groove 2^d, as shown at 24, 25 in Fig. 8.

In each of the constructions above referred to the groove is formed in the bar, but the desired oblique bearing surface might be provided, as shown in Fig. 9, by forming a V-shaped rib 23 for co-operation with a correspondingly shaped groove 26 in the under side of the pin 1^e.

In all of the illustrated embodiments of the invention, as in others which will suggest themselves, there is provided on either the pin or the bar, or on each a relatively oblique bearing surface, so that the pin holding means, such as the spring clip 18, always presses the two parts closely together and compensates for wear of one part with respect to the other and thereby the development of looseness between the two parts is prevented.

I claim as my invention:

1. In a shuttle operating mechanism for an embroidering machine, the combination of a longitudinally movable shuttle actuating pin, a shuttle operating bar, and means to press the pin against the bar, the pin and the bar having a relatively oblique bearing surface, the one against the other, whereby, as the pin and bar become worn at their bearing surface, the pin is pressed closely against the bar and relative lateral movement of the pin is prevented.

2. In a shuttle operating mechanism for an embroidering machine, the combination of a longitudinally movable shuttle actuating pin, a shuttle operating bar, and a spring clip to press the pin against the bar, the pin and the bar having a relatively oblique bearing surface, the one against the other, whereby, as the pin and bar become worn at their bearing surface, the pin is pressed closely against the bar and relative lateral movement of the pin is prevented.

3. In a shuttle operating mechanism for an embroidering machine, the combination of a longitudinally movable shuttle actuating pin, a shuttle operating bar grooved to

receive the pin, and means to press the pin into the groove, the pin and the bar having a relatively oblique bearing surface, the one against the other, whereby, as the pin and bar become worn at their bearing surface, the pin is pressed closely against the bar and relative lateral movement of the pin is prevented.

4. In a shuttle operating mechanism for an embroidering machine, the combination of a longitudinally movable shuttle actuating pin, a shuttle operating bar having a groove with an inclined side to receive the pin, and means to press the pin into the groove, whereby, as the pin and bar become worn, the pin is pressed closely against

the inclined side of the groove and relative lateral movement of the pin is prevented.

5. In a shuttle operating mechanism for an embroidering machine, the combination 20 of a longitudinally movable shuttle actuating pin, a shuttle operating bar having a groove with two inclined sides, and means to press the pin into the groove against the inclined sides, whereby, as the pin and bar 25 become worn at their bearing surface, the pin is pressed closely against the bar and relative lateral movement of the pin is prevented.

This specification signed this 8 day of 30 October A. D. 1919.

HIPPOLYT SAURER.
